UNITED STATES PATENT OFFICE.

TIBERIAS B. M. DOUGHERTY, OF PHILADELPHIA, PENNSYLVANIA.

NON-REFILLABLE BOTTLE.

1,012,826.

Specification of Letters Patent.

Patented Dec. 26, 1911.

Application filed March 28, 1911. Serial No. 617,457.

To all whom it may concern:

Be it known that I, TIBERIAS B. M. DOUGHERTY, a citizen of the United States, residing at Philadelphia, in the county of Philadelphia and State of Pennsylvania, have invented a certain new and useful Improvement in Non-Refillable Bottles, of which the following is a specification.

My invention relates to new and useful improvements in non-refillable bottles, and has for its object to produce a bottle of this character which will be exceedingly simple in construction, comparatively inexpensive in the cost of manufacture, yet strong and durable for the purpose for which it is used.

In constructing this bottle I mount a tube in the neck of a specially constructed bottle, said tube carrying a sliding valve, said valve having mounted therein a secondary valve for closing the former, even though said former valve be open with relation to the tube in which it is mounted.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which—

35 Figure 1, is a side elevation of the upper portion of a bottle in section to clearly illustrate the construction. Fig. 2, a similar view showing the position of the valves when the liquid is being poured from the bottle. Fig. 3, an isometric view of the tube which is mounted in the neck of the bottle. Fig. 4, a similar view of the valve. Fig. 5, a similar view of the secondary valve, and Fig. 6, a plan view of the perforated guard.

45 In carrying out my invention as here embodied, (1) represents the body of the bottle having a neck 2, which is provided with an enlarged portion 3, forming in the interior a guard cavity 4, the bottom wall of which 50 forms an annular flange or shoulder 5 in which is produced an annular depression 6. With the enlarged portion is formed the extension or mouth 7 whose outer wall diverges toward its outer end as indicated by 55 8, thus making a relatively thin portion 9 where said mouth joins with the enlarged

portion. The mouth of the bottle is made thin at this point in order that it may be readily and easily broken if the mechanism is tampered with, and in order that this point may be further weakened when the bottle is being tampered with, yet braced during ordinary handling, I provide a metallic ring 10 which is molded in to the bottle, at the point where the extension 7 joins with the enlarged portion 3.

11 denotes a tube having a flange 12 formed with its upper end and provided with internal oppositely disposed grooves or tracks 13 which extend inward from the upper end of said tube within proximity to the opening 14. This tube is open at both ends and is inserted in the neck of the bottle until the flange 12 seats itself in the depression 6. The diameter of this tube being smaller than the interior diameter of the neck in order to produce a liquid space 15 between the neck and said tube whereby the liquid may reach the opening 14 in the side wall of said tube, produces a space 16 which is unused between the tube and the bottle neck and between the opening 14 and the flange 12, and when the bottle is inverted to pour out the liquid a portion thereof would flow into this space, and in order that this may not happen, I provide a packing 17 of cork or other suitable material which will fill the space 15 from the opening 14 to the flange 12, so that when the bottle is inverted the liquid will flow only 20 to the opening 14. After the tube 11 is inserted the sliding valve 18 is placed in said tube so that the lugs 19 formed with the upper end of said valve, may register with the grooves 13 in the tube 11, thereby causing the opening 19 in the valve 18 and the opening 14 in the tube 11 to be in alinement or register with one another when the bottle is inverted, since the distance from the top of the valve 18 to the opening 19 is 25 equal to the distance from the top of the tube 11 to its opening 14. The faces of the tube 11 are parallel and vertical and although the outer face of the valve 18 is the same as the faces of the tube and snugly 30 fits within said tube, yet the interior face of said valve converges with the interior face toward its upper end, producing a beveled interior side wall 20. The bottom of said sliding valve is closed by the integral wall 21 so that the liquid passing from the bottle to reach the interior of the

35 tube 11 will be held in the valve 18 and will not pass through the valve 18 to the opening 14. The faces of the valve 18 are parallel and vertical and although the outer face of the valve 18 is the same as the faces of the tube and snugly 40 fits within said tube, yet the interior face of said valve converges with the interior face toward its upper end, producing a beveled interior side wall 20. The bottom of said sliding valve is closed by the integral wall 21 so that the liquid passing from the bottle to reach the interior of the

valve must pass through the openings 14 and 19.

In the sliding valve 17 is mounted a secondary sliding valve 22, the interior walls of which diverge toward its upper end, producing a beveled side wall 23 which corresponds with the beveled interior walls 20 of the valve 17, so that when the auxiliary valve 22 is resting in the bottom of the valve 17, the opening 19 of the latter is closed, but when the bottle is inverted and the auxiliary valve rests at the upper end of the valve 17, a space is left between the interior walls of the valve 17 and the exterior walls of the auxiliary valve 22 equal to the difference between the interior diameter of the valve 17 at its upper end and the exterior diameter of the auxiliary valve 22 which space is sufficient to permit the liquid to flow from the bottle. The auxiliary valve may be in the form of a float or a solid body, yet is preferably constructed in the manner here shown comprising a relatively heavy body having a cavity 24 leading from the top thereof, so that when it is attempted to fill the bottle, a certain amount of liquid will run into this cavity, adding its weight to the body of the auxiliary valve, causing said auxiliary valve to close the opening 19 and if the bottle is inverted and a liquid forced into the neck, the cavity 24 will then cause the auxiliary valve to float upon said liquid and close the opening 19. Then again, should the bottle be laid upon its side, the liquid flowing into the neck will carry the auxiliary valve along with it, causing said auxiliary valve to again close the opening and prevent the flowing of the liquid into the interior of the bottle. In order that this mechanism may be held in place and to also prevent its being tampered with, I provide a guard 25 which comprises a body 26 having a plurality of perforations 27 therein and having a flange 28 of relatively soft or untempered material so that after the guard is inserted in the guard cavity 4, the outer face of the body 26 resting upon the flange 5 and upon the top face of the flange 12 of the tube 11, the flange 28 of said guard may be expanded into the guard cavity 4 thereby preventing its withdrawal, to prevent any one tampering with the valves and at the same time acts as a stop for both the valve and the auxiliary valve after they have opened to their full extent.

In practice, the bottle is filled with a liquid and the tube with its valves are inserted, after which the guard is placed in position and this flange expanded with a suitable tube. For shipping, a stopper may be placed in the extension 7. To pour out a liquid the bottle is inverted causing the valve 17 to slide until it abuts the guard, at which time its opening 19 will register with

the opening 14 in the tube 11. At the same time the auxiliary valve 22 will slide from its seat in the valve 17 until it abuts the guard, and as the side walls of the valve and auxiliary valve diverge, and as said auxiliary valve is shorter than the valve proper, then the diameter of the smaller or auxiliary valve will be smaller than the valve proper, at its outer end, leaving a space between the two, permitting the liquid to flow from the bottle through the opening 14 and the opening 19 into the interior of the valve 17, from which point it may flow around the auxiliary valve 22 and through the perforations 27 in the guard.

When it is attempted to fill a bottle with my improved construction, an action reversed to that above described takes place, closing all of the openings and holding the liquid from the interior of the bottle. Should any one attempt to fool with the valve by placing an instrument in the neck any slight pressure upon the extension 7 will cause the same to break from the bottle at its weakest point, which is where it joins with the enlarged portion 3. This mutilation of the bottle may readily be seen by the purchaser, causing him to refuse the bottle with its contents or any of the contents from said bottle.

Of course I do not wish to be limited to the exact details of construction as here shown, as these may be varied within the limits of the appended claims without departing from the spirit of my invention.

Having thus fully described my invention, what I claim as new and useful, is—

1. In combination with the neck of a bottle, a straight walled tube having an opening therein, a valve closed at one end, having an opening in its side wall adapted to register with the opening in the tube, the interior walls of said valve diverging toward its upper end, and a secondary valve having its exterior walls diverging, slidably mounted in the first named valve and adapted to close the opening therein when seated in the lower end of said valve.

2. In a device of the character described a bottle comprising a body, a neck formed therewith having an enlarged portion, the interior of which produces a guard cavity, an annular integral flange formed within said cavity and having an annular depression produced therein, an extension mouth formed with the enlarged portion, a tube having a flange formed with its upper end and provided with a pair of oppositely disposed grooves and an opening in its side wall, a valve closed at one end and having an opening, the interior side walls of said valve diverging toward its upper end, a pair of oppositely disposed lugs formed adjacent the upper ends of said valve, adapted to register with the grooves of the tube, an

auxiliary valve, the exterior side walls of which diverge, having a cavity produced therein, said auxiliary valve being slidably mounted within the first named valve,

5 *perforated guard, and a flange formed therewith, said guard mounted within the guard cavity and resting upon the flange of the tube to prevent the withdrawal of said tube or valves and to act as a stop for*

10 *said valves, the flange of said guard being expanded to prevent its withdrawal from the guard cavity.*

3. In combination with the neck of a bottle, a tube, the interior and exterior walls 15 of which are concentric and straight, said tube having an opening in its side wall intermediate its ends, a valve closed at one end, its exterior wall being concentric with the walls of the tube, its interior walls di- 20 verging, said valve having an opening in its

side wall adapted to register with the opening in the tube when the bottom is inverted, said valve constantly remaining within the tube, a secondary valve slidably mounted in the first named valve and always remaining entirely within said first named valve, the exterior walls of said secondary valve diverging, said secondary valve closing the opening in the first named valve when the bottle is in an upright position, and a guard 25 for retaining the parts in position and limiting the movement of the valves.

In testimony whereof, I have hereunto affixed my signature in the presence of two subscribing witnesses.

TIBERIAS B. M. DOUGHERTY.
